(57) **CLAIM**

The ornamental design for a multiple head lamp, as shown and described.

DESCRIPTION

FIG. 1 is a front perspective view of a multiple head lamp showing a first embodiment of our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a front perspective view of a portion of the multiple head lamp of FIG. 1 as indicated by dashed box 8;

FIG. 9 is a front view of a portion of the multiple head lamp of FIG. 2 as indicated by dashed box 9;

FIG. 10 is a rear view of a portion of the multiple head lamp of FIG. 3 as indicated by dashed box 10;

FIG. 11 is a right side view of a portion of the multiple head lamp of FIG. 4 as indicated by dashed box 11;

FIG. 12 is a left side view of a portion of the multiple head lamp of FIG. 5 as indicated by dashed box 12;

FIG. 13 is a top view of a portion of the multiple head lamp of FIG. 6 as indicated by dashed box 13; and,

FIG. 14 is a bottom view of a portion of the multiple head lamp of FIG. 7 as indicated by dashed box 14.

The features shown in broken lines are portions of the multiple head lamp forming no part of the claimed design. The rectangular broken lines shown in FIGS. 1-14 are included for the purpose of showing enlarged portions of the multiple head lamp and form no part of the claim design.

1 Claim, 13 Drawing Sheets
